UNITED STATES PATENT OFFICE.

CHARLES DEWITT HADCOCK, OF HERMON, NEW YORK.

CHEESE-BANDAGER.

SPECIFICATION forming part of Letters Patent No. 471,756, dated March 29, 1892.

Application filed May 16, 1891. Serial No. 392,988. (No model.)

To all whom it may concern:

Be it known that I, CHARLES DEWITT HADCOCK, a citizen of the United States, residing at Hermon, in the county of St. Lawrence and State of New York, have invented certain new and useful Improvements in Cheese-Bandagers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in devices for use in applying cheese-bandages; and it has for its object to provide a simple and effective device for holding the bandage in place within the cheese-hoop while the same is being filled with curd and during the process of pressing.

To these ends and to such others as the invention may pertain the same consists in the peculiar construction and in the novel combination, arrangement, and adaptation of parts, all as more fully hereinafter described, and shown in the accompanying drawings.

25 The invention is clearly shown in the accompanying drawings, which, with the letters of reference marked thereon, form a part of this specification, like letters of reference indicating like parts throughout the several views, and in which—

Figure 1 is a side view of a cheese-hoop with my improved bandager applied, a portion of the hoop being shown as broken away in order to show the operation of the device.

Fig. 2 is a plan view of the same.

Reference now being had to the details of the drawings by letter, A designates the

cheese-hoop, which is in all respects similar to those which are commonly used in the manufacture of cheese.

B represents a band or ring of sheet metal, consisting of a series of sections *a a*, attached 45 at their ends by means of hinged joints *b b*. This band is provided at intervals upon its outer surface near one of its edges with lugs or projections *c*, which are adapted to rest upon the upper edge of the cheese-hoop and 50 serve to prevent the band from sinking within the hoop.

In use the bandager is contracted, as shown in dotted lines in Fig. 2 of the drawings. The cloth is placed within the hoop and the bandager is then pressed outwardly, forming a continuous hoop or ring which binds against the inner face of the cheese-hoop, and the bandage, which is interposed between the hoop and bandager, will be held smoothly 60 and securely in place.

Having thus described my invention, what I claim to be new, and desire to secure by Letters Patent, is—

The combination, with a cheese-hoop, of a 65 bandager consisting of a band or ring composed of a series of hinged sections and adapted to be pressed in and out to contract and expand the band and provided with a series of outwardly-extending lugs or projections 70 adapted to engage the upper edge of the cheese-hoop and serve as a support for the bandager, substantially as and for the purpose described.

In testimony whereof I affix my signature in 75 presence of two witnesses.

CHARLES DEWITT HADCOCK.
